UNITED STATES PATENT OFFICE.

CHARLES B. WILKINSON, OF NEW YORK, N. Y.

DESIGN FOR A BADGE.

SPECIFICATION forming part of Design No. 25,055, dated January 21, 1896.

Application filed November 16, 1895. Serial No. 568,645. Term of patent 14 years.

To all whom it may concern:

Be it known that I, CHARLES B. WILKINSON, a citizen of the United States, residing in the city, county, and State of New York, have 5 originated, invented, and produced a new and original Design or Pattern for a Badge, which is fully described and represented in the following specification and the accompanying drawing, forming a part of the same.

10 The design consists of representations of six shields arranged upon a circular belt or garter and projecting over both the outer and inner edges of the belt, the six shields bearing respectively emblems of the coats of arms 15 of the six New England States, namely: an anchor, the emblem of the State of Rhode Island; the figure of an Indian erect holding a bow, the emblem of the State of Massachusetts; the head of a stag, the emblem of 20 the State of Vermont; a pine tree, the emblem

of the State of Maine; a ship in stocks, the emblem of the State of New Hampshire; and three vines, the emblem of the State of Connecticut. Across the belt and with both its ends projecting over the belt is a stalk of Indian corn terminating in an ear. The stalk is tied with a ribbon or scroll, having both its ends projecting beyond the belt. 25

What I claim as my invention, and desire to secure by Letters Patent, is— 30

The design for a badge, substantially as herein shown and described.

In testimony whereof I have hereunto set my hand in the presence of two subscribing witnesses.

CHARLES B. WILKINSON.

Witnesses:

ERNEST L. CONANT,
